CLAIM

The ornamental design for a propeller with stepped hub as shown and described.

DESCRIPTION

FIG. 1 is a front perspective view of a propeller with stepped hub;

FIG. 2 is a front elevation view of the propeller of FIG. 1;

FIG. 3 is a rear elevation view of the propeller of FIG. 1;

FIG. 4 is a right side elevation view of the propeller of FIG. 1;

FIG. 5 is a left side elevation view of the propeller of FIG. 1;

FIG. 6 is a top plan view of the propeller of FIG. 1;

FIG. 7 is a bottom plan view of the propeller of FIG. 1; and,

FIG. 8 is a rear perspective view of the propeller of FIG. 1. The broken lines in FIGS. 1-8 represent portions of the propeller with stepped hub that form no part of the claimed design.

1 Claim, 8 Drawing Sheets
